UNITED STATES PATENT OFFICE.

CHRISTIAN HAGANS, OF ERFURT, GERMANY.

DRIVING-AXLE FOR LOCOMOTIVES.

SPECIFICATION forming part of Letters Patent No. 700,038, dated May 13, 1902.

Application filed November 27, 1901. Serial No. 83,925. (No model.)

To all whom it may concern:

Be it known that I, CHRISTIAN HAGANS, manufacturer, a subject of the King of Prussia, Emperor of Germany, residing at Erfurt, in the Kingdom of Prussia, German Empire, have invented certain new and useful Improvements in Driving-Axles for Locomotives, of which the following is a specification.

My invention relates to improvements in driving-axles for locomotives and is represented in the accompanying drawings, Figures 1 to 8, viz:

Fig. 1 is a view and longitudinal section of the driving-axle. Fig. 2 is a front view of the crank. Fig. 3 is a section through the middle of Fig. 1 of the hollow axle. Fig. 4 is a longitudinal section through the hollow axle and its cross-joint. Fig. 5 is a cross-section of the cross-joint. Fig. 6 is a side elevation of the lower part of a locomotive equipped with my improvements. Fig. 7 is a longitudinal central section of the same, and Fig. 8 is a plan view thereof.

It is preferable to construct the driving-axle T' or driving-axles of the locomotive, which are located at a distance from the fixed axles, so as to be adjustable in a radial and movable in a lateral direction. To this end the driving-axle T', Fig. 1, is embraced or surrounded by a hollow axle H, which carries the wheels and is journaled in a revolving frame D, having its fulcrum about the pivot Z. It is thus possible for the locomotive to travel around sharp curves. The halves of the driving-wheel axles T' are connected to the hollow axle or sleeve H by means of a cross-joint, the hollow axle forming the ring of the cross-joint coupling. This form of construction is shown in Figs. 4 and 5.

The sleeve H is made in one piece. The four pins or pivots of the cross-joint are located side by side, and two pins are arranged at the end of each half driving-axle T'. The half-axles T' are ball-shaped at their ends d and fit in the hollow spherical bearings ee'. Each joint is formed by means of a conical pin, the ends of which form two pivots f. This joint-pin extends through the sleeve H and through the ball d and is secured to the sleeve by means of screw-nuts. The parts e' of the ball-bearings for the ball ends d are cup-shaped

and adjustable and are secured by means of wedges g or the like. In order to transfer in this arrangement a lateral displacement of one half of the driving-axle T' directly and without shock to the other half of the same, the adjacent ends of the balls d d are worked out at h, and a body i, worked out on both sides in accordance therewith, is inserted between the two. On reference to Fig. 4 it will be seen that the body i is seated equally in the correspondingly-formed recess h in the ball ends d and that the bottoms of said recesses are concaved, while the opposite ends of the body i are convexed to secure the result hereinbefore set forth. The ends of the joint-pins f are covered by caps k, closely fitted upon the sleeve H to contain and retain lubricating material for the ball-faces d h. Each driving-axle half T' can easily be removed from the sleeve H after the wedges g have been withdrawn and the cups e' removed. The lubricating material is very well protected, and the bearing-faces are secured against dust.

Having now particularly described and ascertained the nature of this invention and in what manner the same is to be performed, I declare that what I claim is—

1. A device of the class specified, comprising a sleeve provided with wheels, an axle consisting of a plurality of sections fitted in the sleeve, and the inner ends of the axle-sections being ball-shaped and the sleeve being slotted, spherical bearings in the sleeve for said ball ends, and wedges adapted to project through said slots and to bear against said spherical bearings for the purpose of adjusting the same.

2. A device of the class described, comprising a sleeve provided with wheels, an axle consisting of a plurality of sections fitted in the sleeve and having ball-shaped inner ends, spherical bearings in the sleeve for said ball ends, and the latter having recesses in their adjacent surfaces, and the bottoms of the recesses being convex, and a body fitted into said recesses and its opposite ends being concave.

3. A device of the class specified, comprising a sleeve provided with wheels, an axle consisting of a plurality of sections inclosed by

said sleeves and having ball-shaped inner ends, spherical bearings in the sleeve for receiving said ball-shaped ends, pins extending through slots in the sleeve and ball-shaped ends respectively, and caps upon the sleeve covering the outer ends of said pins.

5 In testimony whereof I have hereunto set

my hand in presence of two subscribing witnesses.

CHRISTIAN HAGANS.
